Patented Jan. 19, 1915.

UNITED STATES PATENT OFFICE.

FRANZ BLOCKI AND FRANK A. BLOCKI, OF SHEBOYGAN, WISCONSIN.

WINDROWER-ROD CONNECTOR.

1,125,260.

Specification of Letters Patent.

Patented Jan. 19, 1915.

Application filed December 12, 1910. Serial No. 596,977.

To all whom it may concern:

Be it known that we, FRANZ BLOCKI and FRANK A. BLOCKI, citizens of the United States, residing in Sheboygan, in the county 5 of Sheboygan and State of Wisconsin, have invented new and useful Improvements in Windrower-Rod Connectors, of which the following is a description, reference being had to the accompanying drawings, which 10 are a part of this specification.

This invention relates to improvements in windrower rod connectors and more particularly to the connection for coupling windrower rods to a cutting mechanism.

15 One of the objects of this invention is to provide a connector for pivotally fastening windrower rods to a cutting mechanism which is simple in construction and operation and which consists of the minimum 20 number of parts.

A further object of the invention is to provide a windrower rod connector which is adapted to be rigidly connected to a windrower rod and pivotally connected to a 25 cutting mechanism or an attachment therefor or to both an attachment and a cutting mechanism.

With the above, and other objects in view, the invention consists of the connector and 30 its parts and combinations as set forth in the claims, and all equivalents thereof.

In the accompanying drawing in which the same reference characters indicate the same parts in all of the views: Figure 1 is 35 a top view of a portion of a cutting mechanism and guards coupled thereto by the improved connectors; Fig. 2 is a side view thereof; Fig. 3 is a top view of the connector shown connected to a cutting finger and its attachment and to a part of a rod, the 40 finger and its attachments being shown in section; Fig. 4 is an inverted bottom view of the connector shown connected to a rod; Fig. 5 is a central vertical sectional view of 45 the connector and a portion of the rod taken on line 5—5 of Fig. 4; and, Fig. 6 is a front view of the connector and an end view of the rod.

Referring to the drawing the numeral 10 50 indicates the fixed bar of a cutting mechanism, 11 the cutting fingers connected thereto, 12 the finger attachments or guards which are pivotally connected to the fingers by the connector members 13 and 14 the

windrower rods which are carried by the 55 connectors.

The connector consists of a flat body portion 15 having depending side flanges 16 and forwardly extending eyed ears 17 formed integral therewith. The side flanges 60 also extend rearwardly from the body portion and form rearwardly extending side members 18 which depend downwardly and are connected together by the transverse supporting bar 19 forming the rod opening 65 20. The rearwardly extending side members and the transverse bar are also formed integral with the body portion. The windrower rod 14 extends through the rod opening 20 and engages the body portion 70 between the side flanges thereof and is rigidly fastened to said body portion by means of the rivet 21 which passes through rivet openings 22 and 23 provided in the rod end and the body portion respectively. The side 75 flanges of the body portion and the rearwardly and downwardly extending side members thereof serve to prevent the rod from swinging laterally and the transverse bar 19 serves to support the rod and to prevent a downward strain on the rivet 21. The body portion, the flanges, the side members and the transverse bar are so positioned with relation to each other that the opening 80 20 is formed of sufficient size to just permit 85 the insertion of the end of the windrower rod therethrough and have it rest on the upper surface of the transverse bar and also against the lower surface of the body portion 90 as clearly shown in the drawing.

The eyed ears of the connector are adapted to straddle the rear end portions of the finger and the guard and to be pivotally connected thereto by a bolt 24 which extends through the eyes 25 of the ears 17 and 95 through openings 26 and 27 provided in the rear ends of the finger and the guard respectively. This bolt not only serves to pivotally connect the rod to the cutting mechanism but also serves to fasten the guard to 100 the finger thus simplifying the construction.

While the connector is shown as coupling the rod to the guard and the finger, it is to be understood that it may be coupled to either member of the cutting mechanism or 105 to another part thereof without departing from the spirit of the invention.

From the foregoing description it will be

seen that the connector is very simple in construction and is well adapted to perform the functions desired.

What we claim as our invention is:

- 5 1. A connector for a windrower rod, comprising a body portion having an end opening formed therein, arms secured to said body portion and extending outwardly therefrom, rearwardly extending side members integral with said body and adjacent said opening, a transverse bar secured to said members adjacent the opening in the body portion and positioned below the plane of said portion, a seat in said body portion, 15 the windrower rod resting on said transverse bar and said seat whereby movement of said rod with respect to said body portion is prevented and means for rigidly securing said rod in position on the connector.
- 20 2. A connector for a windrower rod, comprising a body portion having an end open-

ing formed therein, arms secured to said body portion and extending outwardly therefrom, a transverse bar adjacent the opening in the body portion, integral therewith and offset therefrom, a recess in said body portion adjacent the opening therein, the windrower rod resting on said transverse bar and fitting within the recess whereby movement of said rod with respect to said body portion is prevented, and means passing through the end of the rod and the body portion for rigidly securing said rod in position on the connector. 25 30

In testimony whereof we affix our signatures, in presence of two witnesses. 35

FRANZ BLOCKI.
FRANK A. BLOCKI.
